UNITED STATES PATENT OFFICE.

ARCHIE LIBERTY, OF AMASA, MICHIGAN.

SAFETY STARTING DEVICE FOR INTERNAL-COMBUSTION ENGINES.

1,148,176.

Specification of Letters Patent. Patented July 27, 1915.

Application filed March 4, 1914. Serial No. 822,360.

To all whom it may concern:

Be it known that I, ARCHIE LIBERTY, a citizen of the United States, residing at Amasa, in the county of Iron and State of Michigan, have invented certain new and useful Improvements in Safety Starting Devices for Internal-Combustion Engines, of which the following is a specification.

This invention relates to internal combustion engines, and more specifically to a safety starting device for use in connection with such engines.

The object of my invention is to provide a device which will be simple in construction and effective in operation so that when the crank of an automobile is turned to start the motor, safety pawls will automatically check the reverse movement of the crank which is sometimes caused by back-fire in this type of engine. A plurality of pawls are provided, the operation of any one of which is sufficient to cause the device to operate as intended.

Other objects of this invention not at this time more particularly enumerated, will be clearly understood from the detailed description and drawings forming a part of this specification.

Furthermore, this invention consists in the novel arrangement and combination of parts more particularly described in the following specification and embodied in the claims appended hereunto and forming a part of this application.

Referring now to the drawings which are merely illustrative of my invention, Figure 1 is a side elevation of my device inclosed in its casing, while Fig. 2 is a longitudinal side elevation of the interior arrangement with the casing in section. Fig. 3 is a cross sectional view taken on the line $\alpha-\alpha$ of Fig. 1, while Fig. 4 is a fragmental detail elevation of the spring abutment and front plate. Fig. 5 is a detail elevation showing the construction of one of the pawls.

Referring further to the drawings wherein similar reference characters designate similar parts throughout the respective views, 1 is a ratchet wheel, rearwardly from which 50 is solidly fixed an auxiliary crank-shaft 2, terminating in a clutch head 2^a. Upon the front face and in the center of said wheel and extending part way therethrough is a hole 3, preferably square, into which main

crank-shaft 4 fits when pushed forward into 55 engagement with said wheel. The shaft 4 is, however, held normally disengaged from said wheel by an open cylindrical spring 5 interposed between the spring abutment 6 fixed fast upon the main crank-shaft, and 60 the flange 7 of the casing portion 8. In continuation of said main crank-shaft is a crank handle 9. At a certain point near the forward end of main crank-shaft 4 is loosely mounted a front plate 10 which is bolted to 65 casing portion 8 by means of nuts 11. Said front plate is provided inwardly therefrom with a lug 12 adapted to engage with slot 13 of plate member 6 when crank is at rest, and to be disengaged by the pushing forward of main crank-shaft 4 when it is desired to crank the engine. Rearwardly from casing portion 8 and surrounding wheel 1 is a ring member 14, and rearwardly from 70 said ring member is a rear plate member 15 loosely mounted about auxiliary crank-shaft 2 and forming a complete casing by being bolted by bolts 16 to ring member 14 and 75 casing portion 8. Fixed to said rear plate member 15 are two supporting rods 15^a by 80 means of which the device is securely mounted to an automobile. The inner circumference of ring member 14 is provided with depressions 17 into which and projecting therefrom are pivotally mounted pawls 85 18, by means of pivots 18^a, said pawls adapted to engage with ratchet wheels 1 to prevent reverse movement thereof. The said pawls are provided on the top side 90 thereof with a flat surface 19 countersunk in a manner adapted to hold in place one 95 end of springs 20, the other end of said springs being engaged with an indentation in the upper wall of depression 17. When the crank is turned to the right the pawls do not operate, but the instant a reverse movement of the ratchet wheel occurs, the pawls are forced by means of the spring members 100 into the ratchets of the wheel which prevents reversing the movement of the crank handle backwardly against the operator.

Having now described and pointed out the new and useful features of my invention, I do not limit myself to the shape of certain parts where the shape is not essential, nor do I restrict myself to the exact details of construction shown and described, but mean and intend to claim all equivalents

and variations thereof not departing in principle from my invention and falling within the purview of the appended claims.

What I claim as my invention and desire to secure by Letters Patent is:

1. In a device of the kind described, in combination, a casing hollowed out cylindrically internally thereof, the inner circumferential wall of said casing provided with a plurality of depressions therein, a pawl pivotally mounted within each of said depressions, a spring interposed between one face of said pawl and the adjacent face of said depression adapted to force the free end of said pawl toward the axial center of said casing, a ratchet wheel mounted within said casing adapted to coöperate with said pawls, an auxiliary crank shaft fixedly mounted upon the rearward face of said ratchet wheel, said ratchet wheel formed with a rectangular socket centrally thereof, a squared main shaft adapted to fit within said socket, a spring abutment fixedly mounted at a certain point upon said main shaft, a housing formed upon said casing, a spring interposed between said abutment and said casing adapted to fit within said housing, a plate member adapted to close said housing, and a crank handle mounted upon said main shaft.
2. In a device of the kind described, in combination, a casing, the inner circumferential wall of said casing provided with a plurality of depressions therein, a spring actuated pawl pivotally mounted within each of said depressions, a ratchet wheel mounted within said casing adapted to coöperate with said pawls, an auxiliary crank shaft fixedly mounted upon the rearward face of said ratchet wheel, said ratchet wheel

formed with a rectangular socket centrally thereof, a squared main shaft adapted to fit within said socket, a spring abutment fixedly mounted at a certain point upon said main shaft, a slot formed within the outer face of said spring abutment, a housing formed upon said casing, a spring interposed between said abutment and said casing adapted to fit within said housing, a plate member adapted to close said housing, a lug formed upon the inner face of said plate member adapted to engage with said slot, and a crank handle mounted upon said main shaft.

3. In combination, a casing, a rotatable member disposed within said casing, an auxiliary crank shaft fixedly mounted upon one face of said rotatable member, said rotatable member formed with a socket centrally thereof, a housing formed upon said casing, a crank shaft arranged to enter said socket adapted to operate said rotatable member, a spring disposed within said housing, an abutment fixed upon said crank shaft adapted to compress said spring in said housing, said abutment formed with a slot in the outer face thereof, a perforated plate member mounted upon said housing, said crank shaft loosely mounted within the perforation in said plate member, and a lug formed upon the inner face of said plate member adapted to engage with the slot in said abutment.

In testimony whereof I affix my signature in presence of two witnesses.

ARCHIE LIBERTY.
